UNITED STATES PATENT OFFICE

ALBERT H. WEIS, OF NYACK, NEW YORK

ELASTIC STRIP ATTACHMENT FOR SEWING MACHINES

Application filed January 4, 1927. Serial No. 158,859.

This invention relates to sewing machines, more particularly to an elastic strip attachment therefor, the object of the invention being to provide an improved attachment 5 adapted to form a pocket from the material of the garment and, simultaneously with the stitching of the pocket, to insert an elastic strip therein.

The invention is particularly useful for inserting a continuous elastic band between the folds of garments, one after another in a continuous fashion without the use of a covering strip, the pocket of the elastic being made by folding the goods of the garment to enclose the elastic strip thus concealing it from view.

In the hemming of knickerbocker bloomers and similar articles, the garment will be folded in a pleat to form a pocket for an elastic strip. In one form of the invention shown herein, such elastic strip may be readily tacked at the start and finish, being entirely free within the pocket between such tacked portions.

25 In the present improvement a very simple change in construction may be made for inserting endless loops of elastic whereby exact sizes may be maintained.

One of the advantages of the present improvement is that the goods may be quickly placed in stitching position, flat and free of fold, and by a simple shift of knee or foot treadle the attachment will automatically fold the goods to form a pocket, thereby avoiding the necessity of inserting the goods into a hem or some particular form of folder. In the present instance the goods are projected into an open guide in overlapping relation, so that three folds of goods are formed, one layer being above another so that the elastic strip may be inserted into either the top or bottom fold as may be desired. It is preferred, however, when operating with a continuous elastic, to insert it into the top fold, whereas when operating with an endless loop of elastic it is preferred to insert it into the bottom fold.

In the hemming of knickerbocker bloomers and the like, manufacturers experience some difficulty in obtaining suitable covering strips

to match the large variety of colors and textures of fabric. Therefore to hem or form a pocket from goods of the garment itself offers considerable advantage, although on the cheaper grades of fabric which are manufactured in much larger quantity, the use of a covering strip has become very popular.

The present invention is an improvement in part upon that shown and described in Letters Patent No. 1,277,004 and No. 1,277,005, dated August 27, 1918, of John P. Weis, in which a two-needle machine of the well-known Metropolitan type is used and in which the elastic strip, after it comes from below the work plate of the sewing machine, is given a right angle turn and passed along a guide to be presented to the needles.

In the drawings accompanying and forming a part of this specification, Fig. 1 is a perspective view of so much of a sewing machine as is necessary to illustrate the present improvement applied thereto; Fig. 2 is a plan view of the work plate and shifting mechanism for operating this improvement; Fig. 3 is a front view of Fig. 1; Fig. 4 is a perspective detail view of the elastic strip tension means; Fig. 5 is a perspective view of the parts for forming the fold in the goods; Fig. 6 is a perspective view of the guide for the goods and the elastic strip; Fig. 7 is an end detail view of the guide for the work and the elastic strip and illustrates the manner in which the garment is folded and the elastic strip fed thereto; and Fig. 8 is a perspective view of the parts as constructed in the present instance to impart tension to an endless elastic loop.

Similar characters of reference indicate corresponding parts in the several figures of the drawings.

Before explaining in detail the present improvement and mode of operation thereof, I desire to have it understood that the invention is not limited to the details of construction and arrangement of parts which are illustrated in the accompanying drawings, since the invention is capable of other embodiments, and that the phraseology which

I employ is for the purpose of description and not of limitation.

The head 1 of the sewing machine carries the needles 2 and presser foot 3. The base of the sewing machine carries throat plate 4, cloth plate 5, cloth plate slide 6 and also the looper thread guide eyelets 7a. A floor treadle bracket 8 is provided carrying a treadle 9 and a treadle rod or chain 10, the upper end of which is connected to an arm 11 secured to a rock shaft 12 suitably mounted in a bracket 13 secured to the cloth plate. A spring 14 surrounds this rock shaft 12 and has one end bent as at 15 to enter the bracket, and its other end bent to enter a collar 16 secured to the rock shaft by suitable screws 17. By adjusting the screws 17 and the collar 16, the tension of the spring 14 may be adjusted. A crank 18 is secured to the shaft 12, as at 19, and to the end of the shaft is also secured a crank arm 20. To this arm 20 one end of a link 22 is connected, the opposite end of this link being connected with a slide bar 23 thereby to slide the bar in the direction of the arrow, Fig. 1. This slide bar is carried by the slide plate 6 and is provided with two slots 25 through which pass screws 26, the bar being free to slide back and forth so that it may be shifted in one direction by the foot treadle 9 and automatically returned to its original position by the spring 14 rocking the shaft 12.

This slide bar 23 has a lateral or rearward extension to which is connected, by screws 27, a U-shaped overhanging guide 30, the plate portion 28 of which is provided with two elongated slots 29 to permit the guide to be adjusted with relation to the needles. The overhanging portion 31 of this guide is provided with slots 32 and 33 to facilitate the entrance and removal of the elastic strip 34. The slot 33 is located at an angle of about 45 degrees to permit the elastic strip to be turned at right angles and in the direction of the line of feed of the goods and thus permits the goods to be folded over and under the elastic strip conveniently. The inclined front edge 35 of the guide prevents the folds of the goods from catching on to that portion of the guide as the goods are fed through the machine. By having the elastic strip pass over and down through the slot 33 and along under the top overhanging wall 31 and out of the slot 32 and over the top portion of the overhanging wall at the delivery end of the guide, the elastic strip is controlled and kept from interfering with the fold of the fabric when it is being projected into the guide.

The location and position of this guide with respect to the needles is important, since it must be as close to the stitching position as possible and yet provide sufficient space between it and the presser foot to permit the goods to fold readily without wrinkle or

shifting so as to produce a smooth finish without twist or unevenness.

Connected to the crank 18 by a screw is a link 37, the opposite end of which is connected to an arm 39 of an angularly formed member 40, which is pivotally supported and hung by a bearing 41 on a stud 42 secured to the bent end 43 of a bracket 44. This bracket is fastened to and supported by a block 45 attached to the bearing 46 of the sewing machine head. The stud 42 may be in the form of a shoulder screw, but as I have preferred to show it herein a plain stud is used riveted in the bracket 44 and provided with a collar 47 to hold the angle member 40 in working position.

Attached to one of the angle parts or arms 39 of this member 40 by screws 48 is the depending projector or projector guide 50 for projecting the goods into the guide 30. A clamp plate 51 is used to clamp the upper end 49 of the swinging projector and this permits enlargement of the screw holes in the upper end 49 of the projector so that adjustment up and down, as well as laterally or edgewise of the projector is provided for, thereby to compensate for different thicknesses of goods and also to control its position in relation to the other parts. The lower part of the projector 50 is bent at right angles as at 50' to project into the guide 30 and the front end of this bent part is rounded or inclined as at 50'', so that when this projector member is in working position, the inclined edge 35 of the guide 30 and the inclined or rounded edge 50'' of the projector 50 form a diverging entrance for the folds of the goods as it feeds through to the stitching position. This feature is especially useful when working on garments that have first been seamed up, as the loose ends of the stitch as it enters the guide members automatically works itself out from between these members free from the guides and thus prevents the hooking on or other interference with the smooth working of the fabric through the machine.

In Fig. 7 the dotted line represents the garment or goods, the bottom layer of which is 52, the intermediate layer is 53, and the top layer is 54, while the elastic strip 34 is shown fed in this instance between the intermediate layer 53 and the top layer 54.

Attached to the slide 23 by screws 55 is a tension release member, generally indicated at 56, for operating against the tension plate 57 carried by the plate 60. This tension plate 57 is under the control of a spring 58 having a nut 59 for regulating the tension and these parts are mounted on plate 60 secured to the slide plate 6 by an angle bracket 61, see Fig. 4.

In the operation of the machine the treadle 9 or knee shift when used, is operated to rock the shaft 12 and swing the projector out of the guide 30 and to the right into the dotted line position 62, Fig. 3. This member can

be swung as high as desired to give clearance space for free manipulation and entrance of the work as it is introduced to the stitching position. At the same time the guide 30 is 5 shifted to the left in the construction shown herein.

The presser foot 3 may or may not be lifted according to the character of the work. If it is desired to lift the foot, it may also be connected to the knee shift when used or the treadle 9, so with one and the same movement the presser foot is operated simultaneously with the operation of the guide and the shifting of the elastic.

15 When doing open work it is not at all necessary to lift the presser foot, one garment being run in right after another. It is merely necessary each time a garment is started, to press the treadle 9 to shift and tack the elastic 20 with one of the needles and to also fold and guide the goods until the end of the garment is reached. The treadle is again actuated, the guiding projector is swung out, the elastic is tacked at the finished end of the garment, 25 the next article immediately succeeding it is tacked and then the goods folded under and over, etc., repeating this operation each time the portion of the garment is passed through the machine.

30 In order to stitch an elastic strip into the pocket or folds of the garment fabric, the action of the feed of the goods between the feed and presser foot is so arranged as to feed more of the goods than the elastic, because the elastic is a narrow strip, narrower 35 in width than the width of the pocket or fold of the goods. Usually a groove 3' is provided in the bottom of the presser foot wide enough to fit the normal width of the 40 elastic strip and deep enough to permit the elastic to slip and enable the goods to feed over the elastic as it is retarded from feeding by the tension on the elastic strip. Thus it will be seen that when tension is applied 45 to the elastic strip the goods can be gathered on to the elastic by the feed of the machine, which permits controlling the size of the finished garment. Some elastic strips have more elasticity than others, sometimes as 50 much as 300% stretch. By means of the groove in the foot, in combination with the amount of tension applied to the elastic, more or less gathers can be provided to suit the requirements. Normally, however, if the 55 same length of goods and elastic strip is fed through the machine, there would be no gathers. On the other hand, when tension is applied to the elastic strip, the elastic strip in its normal condition is shorter than the 60 length of the garment fabric, which gathers the goods accordingly. It therefore will be understood that when the tension is released on the elastic strip during the tacking operation, a plain portion of the work will result. On the other hand, if the elastic is

shifted from under the needle while it is under tension, then the work will be gathered where the tacking stitches occur.

When the elastic is shifted the tension on the elastic is released to permit the elastic to be readily shifted under the needle. In some instances, however, it is not necessary to release the elastic. The tension release 56 can be omitted and a continuous tension will in that case be applied throughout the entire 75 length of the elastic. In this instance, however, no plain portion of work will appear at each position where the elastic is tacked to the goods, which offers some disadvantage when the garment is seamed up as there is more bulk of goods at the junction of the joining of the garment. It is therefore optional to employ the tension release feature to gather the goods throughout the entire 80 length, depending upon the conditions under 85 which the machine is operating and the character of the goods being worked upon.

When it is desired to stitch endless loops of elastics to garments that have already been closed, I provide the projector 50 with 90 an open slot 63 and also an open slot 64. Then by passing the endless loop of elastic down through the slot 64 and up through the slot 63 and underneath the presser foot 3, it is an easy matter to stitch the endless 95 loops into the folds of the goods.

When operating on endless loops it is optional whether the tension is applied to the elastic by hand or mechanically, for the reason that the size of the garment is already 100 established at the time the garment is closed, and as the elastic strips are cut to the desired length before the ends are joined together to make the individual pieces, the size is also predetermined so that the matter of applying 105 tension during the stitching operation is not so important as with the method of stitching the continuous length elastic to the open garments. When the open garments are being stitched, it is necessary to control the amount 110 of gathers the garment will have, which is controlled by the amount of elastic strip length that is permitted to feed through with respect to the length of goods feeding through at the same time. That is to say, 115 greater tension on the elastic will effect a greater amount of gathers in the garment, the length of elastic fed through under heavy tension being less than that fed through under a light tension.

To tension the circular endless elastic strip, see Fig. 8, I provide a member consisting of a spring plate 65 attached to the collar 47 by a screw 66, passing through an elongated slot 67, which permits suitable adjustment. This collar being relatively stationary and secured to the stud 42, it will be understood that as the member 50 swings to the right away from the spring 65, the tension on the circular elastic strip represented by 68 is re- 120 125 130

leased. That is to say, the tension opens each time this member is shifted to the dotted line position indicated by 62. This action, being simultaneous with the opening or shifting of the guide members, takes place at the starting and finishing of each stitching operation.

From the foregoing, it will be understood that when operating upon garments that have been closed, a portion of the elastic strip is first inserted in the slots 63 and 64, and then under the presser foot with another portion under the spring 65 so that when the guide member is shifted to working position, tension will be applied to the elastic strip.

To control and hold the projector or projector guide 50 in working position, I employ a spring 69 connected at one end to the link 37 and at the other end to the bracket 44. The tension of this spring is sufficient to cause the bend in the goods and at the same time prevent the goods from being clamped in between the guide members as it feeds through. The tension of this spring is light enough also to permit seams to pass through as well as to permit the guides to open when the starting end of a seam comes along in contact with the rounded portion 50' of the projector and inclined part 35 of the guide. To permit this slight movement, the link 37 may be slotted at 72 to permit endwise movement of the link 37, independent of the rock shaft 12.

In the operation of the attachment shown and described, it will be understood that the 35 rocking movement imparted to the shaft 12 of the shifting mechanism shifts the projector into the dotted line position to the right of the needles, see Fig. 3. Simultaneously with this movement, the U-shaped guide 30 is shifted to the left, so as not only to carry the elastic strip over into the path of the left hand needle, but at the same time to shift it to a position to partly leave the fold of the goods. This shifting of the U-shaped guide when operating on circular work is of special importance, as it permits free entrance and removal of each garment. The shifting of these members in opposite directions also leaves an open space for the manipulation of the work and is accomplished by having the arms or cranks 18 and 20 one above and the other below the axis of the shaft 12.

It will be understood, of course, that the stitching mechanism includes the necessary under thread mechanism, such as looper mechanism, and that the goods or garment and elastic strip are fed to and from the stitching mechanism by suitable feed mechanism, which is deemed not necessary to be shown herein, as they are common in the elastic strip feeding patents of John P. Weis, two of which are hereinbefore referred to.

It is to be understood that by describing in detail herein any particular form, structure or arrangement, it is not intended to

limit the invention beyond the terms of the several claims or the requirements of the prior art.

Having thus explained the nature of my said invention and described a way of constructing and using the same, although without attempting to set forth all of the forms in which it may be made, or all of the modes of its use,

I claim:

1. In an elastic strip attachment for sewing machines, the combination of means for folding the work for the reception of an elastic strip and comprising a pair of cooperating guide members one pivoted for swinging movement only toward and from the other, means connected with the swinging guide member and means connected with said last means for shifting it and thereby swinging the guide member and freely shiftable at the will of the operator while leaving the hands of the operator free to control the work.

2. In an elastic strip attachment for sewing machines, the combination of means constructed to fold the work into a plaited pocket for the reception of an elastic strip and comprising a pair of cooperating guide members one pivoted for swinging movement only toward and from the other, means connected with the swinging guide member and means connected with said last means for shifting it and thereby swinging the guide member and freely shiftable at the will of the operator while leaving the hands of the operator free to control the work, and means carried by one of said guide members for guiding the elastic strip.

3. In an elastic strip attachment for sewing machines, the combination of means constructed to fold the work into a plaited pocket for the reception of an elastic strip and comprising a pair of guide members one projecting into the other and one pivoted for swinging movement only toward and from the other, means connected with the swinging guide member and means connected with said last means for shifting it and thereby swinging the guide member and freely shiftable at the will of the operator while leaving the hands of the operator free to control the work, and means carried by one of said guide members for guiding the elastic strip.

4. In an elastic strip attachment for sewing machines, the combination of means constructed to fold the work into a plaited pocket for the reception of an elastic strip and comprising a pair of guide members one of U-shaped form and the other projecting thereinto and one shiftable toward and from the other, means for shifting said shiftable guide member, and means carried by the U-shaped guide member for guiding the elastic strip to and from the interior of said guide member.

5. In an elastic strip attachment for sewing machines, the combination of means for

5 folding the work for the reception of an elastic strip and comprising a pair of laterally shiftable guide members one of U-shaped form and the other projecting thereinto, means for simultaneously shifting said guide members toward and from each other, and means carried by said U-shaped guide member for guiding the elastic strip.

6. In an elastic strip attachment for sewing machines, the combination of means for 10 folding the work for the reception of an elastic strip and comprising a pair of laterally shiftable guide members one recessed and one projecting into said recess and one supported for swinging movement only, and means for simultaneously shifting said guide members toward and from each other.

7. In an elastic strip attachment for sewing machines, the combination of a slide, 15 means for shifting the slide, a U-shaped guide member carried thereby and movable therewith, and a swinging guide member cooperating with said guide for folding the material and connected with said slide operating means, whereby it is swung.

8. In an elastic strip attachment for sewing machines, the combination of a slide, means for shifting the slide, a U-shaped guide member carried thereby and movable therewith, a swinging guide member cooperating with said guide for folding the material and connected with said slide operating means whereby it is swung, and means for directing an elastic strip to one of said guide members.

35 9. In an elastic strip attachment for sewing machines, the combination of a slide, means for shifting the slide, a U-shaped guide member carried thereby and movable therewith, a swinging guide member cooperating with said guide for folding the material and connected with said slide operating means whereby it is swung, tension means for the elastic strip, and means cooperating with the slide for releasing said tension means when it is desired to shift the elastic.

40 10. In an elastic strip attachment for sewing machines, the combination of a slide, a U-shaped guide carried thereby and movable therewith, a swinging guide adapted to project into said U-shaped guide, and means for moving both of said guides simultaneously toward and from each other.

45 11. In an elastic strip attachment for sewing machines, the combination of a slide, a U-shaped guide carried thereby and movable therewith, a swinging guide adapted to project into said U-shaped guide, means for moving both of said guides simultaneously toward and from each other, and comprising a rock shaft, and means for operating said rock shaft.

50 12. In an elastic strip attachment for sewing machines, the combination of a slide, a U-shaped guide carried thereby and movable therewith, a swinging guide adapted to pro-

ject into said U-shaped guide, means for operating both of said guides simultaneously toward and from each other, and comprising a rock shaft, means for operating said rock shaft, and means for directing an elastic strip to one of said guides. 70

13. In an elastic strip attachment for sewing machines, the combination of a slide, a U-shaped guide carried thereby and movable therewith, a swinging guide adapted to project into said U-shaped guide, said guides constructed to form a plaited pocket, means for operating both of said guides simultaneously toward and from each other and comprising a rock shaft, means for operating said rock shaft, means for directing an elastic strip to one of said guides, and means for tensioning said strip. 75

14. In an elastic strip attachment for sewing machines, the combination of a slide, a U-shaped guide carried thereby and movable therewith, a swinging guide adapted to project into said U-shaped guide, means for operating both of said guides simultaneously toward and from each other and comprising a rock shaft, means for operating said rock shaft, means for directing an elastic strip to one of said guides, means for tensioning said strip, and means cooperating with the guide operating means for releasing the tensioning means when it is desired to shift the elastic. 80

15. In an elastic strip attachment for sewing machines, the combination of a slide, a U-shaped guide carried thereby and movable therewith, a swinging guide adapted to project into said U-shaped guide, means for operating both of said guides simultaneously toward and from each other and comprising a rock shaft, means for operating said rock shaft, means for directing an elastic strip to one of said guides, means for tensioning said strip, and means cooperating with the guide operating means for releasing the tensioning means when it is desired to shift the elastic, said U-shaped guide having slots for guiding the elastic strip into the interior of the guide. 95

16. In an elastic strip attachment for sewing machines, the combination of a slide, a U-shaped guide carried thereby and movable therewith, a swinging guide adapted to project into said U-shaped guide, said guides constructed to form a plaited pocket, means for operating both of said guides simultaneously toward and from each other and comprising a rock shaft, means for operating said rock shaft, means for directing an elastic strip to one of said guides, means for tensioning said strip, and means cooperating with the guide operating means for releasing the tensioning means when it is desired to shift the elastic, said U-shaped guide having slots for guiding the elastic strip into the interior of the guide, and said cooperating guides having diverging meeting edges for facilitating the passage of the goods. 100

105

110

115

120

125

130

17. In an elastic strip attachment for sewing machines, the combination of a pair of guides located adjacent to the needle of the machine and cooperating to form a pleat in the goods thereby to form a pocket for the reception of an elastic strip, one a sliding guide shiftable toward the outer side of the needle and the other swinging toward the inner side thereof, means connected with one of said guide members and means connected with said last means for shifting it and thereby the guide member connected therewith toward and from the other guide member, said last means being freely shiftable at the will of the operator while leaving the hands of the operator free to control the work, and means for directing an elastic strip to the pocket. 70
18. In an elastic strip attachment for sewing machines, the combination of a pair of guides located adjacent to the needle of the machine and cooperating to form a pleat in the goods thereby to form a pocket for the reception of an elastic strip, one a sliding guide shiftable toward the outer side of the needle and the other swinging toward the inner side thereof, means for operating both of said guides simultaneously toward and from each other into overlapping relation, and means carried by one of said guides for guiding an elastic strip to the pocket. 75
19. In an elastic strip attachment for sewing machines, the combination of a pair of guides located adjacent to the needle of the machine and one a swinging guide and the other a sliding guide and cooperating to form a pleat in the goods thereby to form a pocket for the reception of an elastic strip, the sliding guide shiftable toward the outer side of the needle and the swinging guide toward the inner side thereof, means for operating both of said guides simultaneously toward and from each other, and means carried by one of said guides for guiding an elastic strip into the interior of said guide. 80
20. In an elastic strip attachment for sewing machines, the combination of a pair of guides cooperating to form a pleat in the goods thereby to form a pocket for the reception of an elastic strip, means for operating both of said guides simultaneously toward and from each other, and means carried by one of said guides for guiding an elastic strip to the pocket, said guide operating means comprising a rock shaft linkage pivotally connected with both of the guides. 85
21. In an elastic strip attachment for sewing machines, the combination of a pair of guides cooperating to form a pleat in the goods thereby to form a pocket for the reception of an elastic strip, means for operating both of said guides simultaneously toward and from each other, means carried by one of said guides for guiding an elastic strip to the pocket, means for tensioning said elastic strip, said guide operating means comprising a rock shaft and linkage connection with the guides, and means cooperating with said operating means for releasing the tension when it is desired to shift the elastic. 90
22. In an elastic strip attachment for sewing machines, the combination of means for folding the work for the reception of an elastic strip and comprising a pair of cooperating guide members shiftable toward and from each other, means under the control of the operator for shifting said guide members away from each other and including a pair of links pivotally connected to the guide members and automatically-operative means for shifting said guide members toward each other, and means for directing an elastic strip to the fold of the work. 95
23. In an elastic strip attachment for sewing machines, the combination of means for folding the work for the reception of an elastic strip and comprising a pair of cooperating guide members, one shiftable toward and from the other, means under the control of the operator for shifting said guide member in one direction and automatically-operative means for shifting the guide member in the opposite direction, means for directing an elastic strip to the fold of the work, means for tensioning said elastic strip, and means operated by the guide-shifting means for releasing the tensioning means at a predetermined time. 100
